UNITED STATES PATENT OFFICE

EDWARD H. MURPHY, OF HONOLULU, TERRITORY OF HAWAII, ASSIGNOR OF ONE-HALF
TO CHARLES L. CRAWFORD, OF HONOLULU, TERRITORY OF HAWAII

COPY-SHEET HOLDER

Application filed September 30, 1924. Serial No. 740,815.

This invention relates to a copy sheet holder as used principally by stenographers and typewriters to hold the copy in a visible position before them, and particularly to such holders which are provided with manually controlled mechanism to move the copy a line or so at a time at the will of the operator.

The objects of my invention are to provide an improved holder of this type, very simple and cheap to construct, which may be controlled either by the hand or the foot of an operator, which will provide for quick and easy insertion or adjustment of the copy sheet, and which will present an enlarged image of the line to be copied.

The above features together with others which will appear as the description proceeds are secured in the apparatus shown in the drawings hereto and in which:

Figure 1 is a front view of my copy holder as it would appear if standing on a desk in front of an operator.

Figure 2 is a side view of Figure 1.

Figure 3 is a rear view of a portion of the apparatus showing the interior mechanism.

Figure 4 shows an optional arrangement of the magnifying element and Figure 5 is a perspective sketch of the foot treadle control.

Briefly stated my apparatus consists of an upright frame for holding the copy sheet before the eyes of an operator with means for advancing the sheet line by line and a set of magnifiers or mirrors for throwing an enlarged image of each line to the observer.

In the embodiment shown in the drawing the frame takes the form of a light metal rectangular box 1 enclosed by a sheet metal front plate 2 and a similar rear plate 3.

To insure the frame standing upright on a desk, I provide a hinged foot 4 at the front of the frame and which may be folded flat against the frame as indicated at 5 when not in use.

This foot preferably has a lower flange 4' to bear against the desk 6 and a screw hole 7 so that it may be screwed to the desk if desired.

At the upper end of the frame are two

revolvable rollers 8 and 9 which grip the copy sheet 10 and carry it upward as the rollers are revolved.

The copy sheet lies against the front plate 2 and passes under a bridge or aligning strip 11 of sheet metal as shown and the large roll 8 is preferably rubber covered and is provided with a knob 12 for turning it (one way only) by hand and also a foot or hand operated mechanism, described later, for giving it fractional turns in order to advance the copy sheet upward line by line.

The roll 8 turns freely to the right for gripping the copy sheet but cannot be reversed as a ratchet housing 13 surrounds the hub 14 of the knob and contains suitable ratchet mechanism acting on the hub to prevent reverse turning of the knob and roll.

The small roll 9 is carried in bearings 15 at both ends formed at the ends of flat springs 16 and which resiliently press the small roll against the large one for gripping the copy sheet but permit the small roll to be bodily lifted from the large roll upon pressing a release lever 17 pivoted in a bracket 18 on top of the frame and having a link 19 engaging a reduced portion 20 of the small roll.

Thus, when the lever is pressed the copy sheet is free for removal or for adjustment to insure the alignment of its text lines with the bridge member 11.

Arranged across the front of the frame and over the copy sheet is a pair of mirrors 21 and 22 carried on arms 23 which extend through slots 24 in the front plate so that they may be pulled in or out to adjust the mirrors to or from the copy, the arms being guided by a pin or lug 25 and secured in adjusted position by thumb screws 26.

The mirrors are adjustably pivoted to the arms so that they may be revolved to any position and stay in place by friction of the joint, and the lower mirror is a magnifying one, that is, it is concaved in one direction so as to lengthen out all the letters of a line of the copy when the mirrors are properly adjusted to project the reflected image to the observer seated before it, and as indicated at 27 in Figure 1 of the drawing.

In place of the reflectors as described, the

magnifying element may be a convex refracting strip of glass 28 pivotally mounted on the arms as indicated in Figure 4 of the drawing.

To actuate the roll 8 and progressively advance the copy sheet upward, I provide a square rod 29 slidably mounted inside of the frame and forced into contact with the rubber covering of the roll by a flat spring 30 so that when this rod is pulled downwardly, it will frictionally grip the roll and revolve it slightly, but upon being pushed upwardly will slide over the roll on account of the roll being locked against reverse movement by the ratchet 13.

15. To pull the rod downward, it is pivoted at its lower end to a rocker arm 31 carried by the frame and the outer end of the rocker arm projecting through a slot 32 in the rear plate 3 is pivoted to a link 33 in turn pivoted to a hand lever 34 which in its turn is pivoted to the side of the frame at 35 so that by moving the hand lever the link 33 will be forced upward and will pull the rod 29 downward to revolve the roll 8.

20. The rod is returned by a spring 36 hooked to the top of the frame and to a bracket 37 secured to the rod, and the bracket extends in the form of a binding post 38 through a slot 39 in the side of the frame for the reception 25 of a wire 40 secured by a thumb screw 41 in the end of the post. (Spring 36 has been omitted from Figure 2 to prevent confusion.)

30. This wire 40 is preferably a small cable and extends along side the desk, or through a small hole drilled through it, to the floor where it connects to a foot pedal 42 (see Figure 5) hinged at 43 to a supporting board 44 preferably equipped with spikes or pins 45 to keep it from slipping out of place.

35. In setting the device, the wire is pulled through the binding post 38 until the pedal 42 is lifted as shown and then the wire is firmly secured to the post by the screw 41 with the arrangement described a pressure 40 of the foot on the pedal pulls the rod 29 and advances the roll 8.

45. The hand lever 34 operates simultaneously with the foot lever and either control may be used. The hand lever is made in two parts 50 with the forward part pivoted to the rearward part at 46 and hooked over it at 47 like any trunk brace so that when it is desired to use the foot pedal only the projecting end 34' of the lever may be folded up along side 55 the frame as indicated by the arcuate dotted line.

50. To adjust the amount of movement of the copy sheet each time the lever or pedal is pressed, two devices are provided—a rough 40 setting being obtained by a sliding nut 48 adjustable by means of a thumb screw 49 working in a slot 50 of the lever retaining strap 51 so that the downward or return movement of the rear end of the lever is 55 determined, and a thumb screw 52 at the top

of the frame is adjustable against the upper end of the sliding rod 29 also to limit its return movement and serves as a fine adjustment so that a very precise fractional movement of the roller may be had.

70. In contemplating my invention as set forth, it will be apparent that many modifications in the mechanical details may be made without departing from the spirit of the invention, and any such are intended to be embraced in my appended claims.

75. I claim:

1. In a copy sheet holder, a frame, a main roller carried thereby, an auxiliary roller, 80 spring means for yieldingly holding the auxiliary roller against the main one, said auxiliary roller having a reduced portion, a link connected to the reduced portion, and a lever connected to the link for raising the auxiliary roller from the main roller.

85. 2. In a copy sheet holder, a frame, a main roller carried thereby, a member yieldingly held in frictional engagement with the roller, a lever for reciprocating said member, an adjustable stop for limiting the movement of 90 the lever in one direction, and a second adjustable stop for limiting the movement of the member in one direction.

95. 3. In a copy sheet holder, a frame, a roller, a member operatively connected to the roller, a lever operatively connected to the member and being pivotally carried by the frame, a slotted guide strap for the lever, and an adjustable stop carried by the strap and slidable 100 in the slot for limiting the movement of the member in one direction.

105. 4. In a copy sheet holder, a frame, a roller, a member operatively connected to the roller, a lever operatively connected to the member and being pivotally carried by the frame, a slotted guide strap for the lever, an adjustable stop carried by the strap and slidable in the slot for limiting the movement of the member in one direction, and a screw adjustably carried by the frame and acting as a stop 110 for the member.

115. EDWARD H. MURPHY.
